UNITED STATES PATENT OFFICE.

THOMAS A. BOYD AND HAROLD A. BOYD, OF GLASGOW, SCOTLAND.

APPARATUS FOR CONTROLLING THE UNWINDING OF YARN.

1,277,690.

Specification of Letters Patent. Patented Sept. 3, 1918.

Application filed March 25, 1918. Serial No. 224,600.

To all whom it may concern:

Be it known that we, THOMAS ALEXANDER BOYD and HAROLD ARTHUR BOYD, subjects of the King of the United Kingdom of 5 Great Britain and Ireland, and both residing at Shettleston, Glasgow, Scotland, have invented a certain new and useful Improvement in Apparatus for Controlling the Unwinding of Yarn, of which the following is 10 a specification.

This invention refers to apparatus for controlling the unwinding of yarn from a hank carried upon a reel.

According to the invention the reel is so 15 mounted and means are provided for applying drag thereto in such wise that upon an undue strain being put upon the yarn the drag upon the reel will be relieved wholly or partially so that there will be less liability 20 to breakage of the yarn.

Figure 1 of the accompanying drawings is a side elevation of a reel in a swing holder. Fig. 2, is a side elevation of a reel in a fixed holder.

25 Referring to Fig. 1, 1 denotes the axle of a reel 2 carrying a hank 3 of thread or yarn. 4 denotes a brake wheel as mounted on the axle 1 though it may be mounted on the reel boss. The reel 2 is mounted in a 30 vertical U-shaped bracket 5 or cradle; the axle 1 running freely in a gab 5' formed at the top of each limb of the U-shaped bracket 5. On each of the outer sides of the U-shaped bracket is formed a V-shaped projection 5² at some distance below the axle 1. On a rail 6, which is part of the framing of 35 a winding machine, is mounted horizontally and at right angles to said rail a pair of arms 7 at the free end of each of which is 40 formed a V-shaped gab 7'. These arms 7 receive the U-shaped bracket 5, the projections 5² resting in the gabs 7'. Behind the 45 brake wheel 4 is fixed on one of the arms 7 a brake 8 covered with flannel or like material. On the opposite side of the reel to 50 that on which is the fixed brake is mounted a rod 9 parallel with the axis of the reel 2 at a suitable distance from the reel and preferably at a higher level than the axis of the 55 reel.

The bracket 5 is free to swing on the gabs 7' and is controlled by a counterweight 10 which presses the brake wheel 4 against the fixed brake 8.

55 It will be evident that when the thread is being drawn from the reel over the rod 9 in

front, any undue strain on the yarn will withdraw the brake wheel 4 partially or wholly off the fixed brake 8 and thus relieve the drag on the yarn, and that, if the tension be relieved, the brake wheel 4 will fall back against the fixed brake 8 and the yarn will receive drag as previously. By means of an adjusting screw 11 the bracket 5 and reel 4 are prevented from being drawn by 60 the yarn too far from the fixed brake 8 so that with the relief of undue tension on the yarn the fixed brake may at once act.

In Fig. 2, 2 denotes a reel, 3 a hank of 65 yarn and 4 a brake wheel as described with 70 reference to Fig. 1. The reel 2 is mounted between a pair of vertical stands 12 each having a gab 12' at the upper end, the axle 1 of the reel 2 resting on the gabs 12'. The gabs 12' are made wider than the diameter 75 of the axle and with a slight incline as shown by dotted line 13 so that the axle will normally lie near the lower end of the gabs 12'. Behind the gabs 12' is fixed on 80 one of the vertical stands 12 a brake 14 as 85 described in connection with Fig. 1 and this brake 14 is so adjusted that the brake wheel 4 of the reel rests against the brake 14 and not against the back of the adjacent gab 12'. The gabs 12', as also the gabs 7', afford 90 mouths or openings from the bottom walls of which the reels are removably supported. On the side of the reel opposite to the fixed 95 brake is fixed at a suitable height a rod 9 parallel with the axle 1 of the reel 2. The yarn from the hank is drawn over the rod 9 to the winding mechanism. When any undue strain comes upon the yarn, the reel 2, being free to move slightly away from the fixed brake 14, is relieved from the latter. 95 As soon as the undue strain on the yarn is relaxed, the reel will resume its contact with the fixed brake.

What we claim is:

1. For controlling the unwinding of yarn, 100 in combination, a hank-carrying reel rotatable in paying out the yarn, a brake-wheel rotatable with said reel, a fixed brake against which said brake wheel normally rests, and a mount for said reel and said 105 brake reel including gabs from the bottom walls of which said reel and brake wheel are movably supported, thus permitting movement of said brake-wheel away from said fixed brake when the yarn is subjected 110 to undue strain.

2. A yarn unwinding apparatus compris-

ing a rotatable hank-carrying reel, combined with a brake-wheel rotatable with said reel, a fixed brake with which said brake-wheel is normally in contact, a yarn guide on the side of said reel opposite said brake and arranged above the axis of said reel so that an unusual tension on the yarn guided by said guide will move said brake-wheel away from said brake, a pivoted support for said reel and brake wheel, a counterweight on said pivoted support, and a stop for limiting the swinging movements of said support when it is displaced by unusual tension on the yarn, said pivoted support being returned to its normal position by said counterweight when the unusual tension is relieved.

3. For controlling the unwinding of yarn from a hank, in combination, a hank-carry-

ing reel, a brake-wheel rotatable with said reel, a fixed brake against which said brake-wheel normally rests, and a pendulous support for said reel and brake-wheel, said support being pivoted on an axis parallel to and in substantially the same vertical plane as the axis of said reel and brake-wheel, and being adapted to permit movement of said reel and brake-wheel in an arcuate path away from said fixed brake when the yarn is subjected to undue strain.

In testimony whereof we have signed our names to this specification in the presence of two subscribing witnesses.

T. A. BOYD.
